MYRON H. CLARK, OF HASTINGS-UPON-HUDSON, NEW YORK, ASSIGNOR TO GOODYEAR'S METALLIC RUBBER SHOE COMPANY, A CORPORATION OF CONNECTICUT.

RUBBER-SOLE CANVAS SHOE.

1,293,337.

Specification of Letters Patent.

Patented Feb. 4, 1919.

Application filed November 9, 1915. Serial No. 60,476.

To all whom it may concern:

Be it known that I, MYRON H. CLARK, a citizen of the United States, residing at Hastings-upon-Hudson, county of Westchester, State of New York, have invented certain new and useful Improvements in Rubber-Sole Canvas Shoes, of which the following is a full, clear, and exact description.

This invention relates to rubber-sole canvas shoes.

The object of the invention is to provide an article of such footwear in which the insole is so constructed as to constitute a fulcrum for the upper, so that a portion of the pull of the upper under movements of the wearer's foot will be horizontally outward instead of the whole pull being vertically upward, as hitherto. Thus a portion of the strain is distributed over the entire united surfaces of the upper and insole and consequently the line of cement or other securing means between the upper and outsole is relieved of a corresponding amount of strain.

In the ordinary rubber-sole shoe having a fabric upper, such as canvas and the like, the upper is turned inward at the edge over the edge of the insole and cemented firmly to the outsole, the line of cement at the joint between the upper and outsole bearing all of the strain when the shoe is flexed in conforming to the movements of the wearer's foot, so that it eventually is loosened and permits separation of the upper from the outsole.

To obviate the above described disadvantage, I extend the insole outwardly farther than has hitherto been the custom and firmly cement the upper to the marginal portion of the insole, said extended edge forming a fulcrum upon which the upper bears and pivots to a certain extent, so that the force exerted by the upper in flexing and tending to separate the upper from the outsole, has a component parallel with the insole and therefore is in part transferred from the line of cement between the upper and outsole to the entire cemented surface between the upper and insole, thus equalizing the strain between said cemented surface and said line of cement, and consequently, enhancing the long life of the joint between the upper and outsole.

The invention can be readily understood from the following description taken in con-

nnection with the accompanying drawing, in which

Figure 1 is a side elevation of a shoe embodying my improvements;

Fig. 2 is an enlarged cross-sectional view of the parts shown in Fig. 1.

Referring now to the drawings in which like characters of reference designate similar parts, a shoe is shown comprising a fabric upper 10, the edge of which is turned inwardly and cemented as shown at 11, to a rubber sole 12.

In carrying out the invention, I provide an insole 13, the edge of which is extended as shown at 14 to nearly overhang the edge of the outsole, the bottom face of the edge 14 of said extended portion being cemented, as shown at 15, to the inturned edge of the fabric upper. A filler 15', which is customarily formed of rag stock is inserted between and secured to the insole and outsole, there being a layer of rubber treated fabric 16 on the bottom face of the filler to enhance union between the filler and outsole during vulcanization.

By extending the edge of the insole as shown, the edge becomes a fulcrum, upon which the upper pivots somewhat, so that the pull of the upper is in part exerted in a direction parallel to the insole and thus distributed, due to its direction over the entire cemented surface 15 between the insole and upper, thus relieving the line of cement 11 between the upper and outsole of this portion of the strain which hitherto had been borne solely by said line of cement.

The insole may be stiffened throughout, or stiffened marginally if desired, to promote its resistance to flexing and hence promote a better fulcrum action of the edge of the sole, but this is not essential, as the insole may be formed as is customary, so long as the edge is extended sufficiently outward to function as a fulcrum for the upper, as above described.

During vulcanization, the union between the rubber outsole and fabric upper and between the insole and fabric upper becomes unitary and integral with both parts by setting of the cement, so that a strong watertight joint exists between the parts. Various modifications may be resorted to, it being simply necessary to the practice of the invention, that the shoe embody a fabric up-

upper, a vulcanized rubber outsole, and an insole having an extended edge acting as a fulcrum for the upper.

What is claimed is:

- 5 A shoe comprising a non-vulcanizable fabric upper, an extended, relatively-stiff outer sole of rubber compound, an insole stiffened to promote its resistance to flexing at its margins, the margin of said upper being turned inwardly between said soles, a

layer of rubber cement on each side of said margin of the upper, a filler within the space formed by said soles and the edges of said margin of the upper, and a layer of fabric coated with cement and disposed between the 15 filler and outer sole, said parts being vulcanized thereby combining the component parts into a unitary structure.

Signed at New York, N. Y., Nov. 6, 1915.
MYRON H. CLARK.
